CLAIM

The ornamental design for a hamper, as shown and described.

DESCRIPTION

FIG. 1 is a top front perspective view of a hamper showing my new design;

FIG. 2 is a rear perspective view of the hamper as seen in FIG. 1;

FIG. 3 is a top rear perspective view of the hamper as seen in FIG. 1;

FIG. 4 is a front view of the hamper as seen in FIG. 1;

FIG. 5 is a rear view of the hamper as seen in FIG. 1;

FIG. 6 is a side view of the hamper as seen in FIG. 1, the other side view being a mirror image of FIG. 6;

FIG. 7 is a top view of the hamper as seen in FIG. 1;

FIG. 8 is a front perspective view of the hamper from below as seen in FIG. 1; and,

FIG. 9 is the rear perspective view of the hamper from below as seen in FIG. 1.

(Continued)

The broken lines shown in the figures are for the purpose of illustrating portions of the hamper, which form no part of the claimed design.

1 Claim, 9 Drawing Sheets
